UNITED STATES PATENT OFFICE.

LEWIS KELMUND THURLOW AND JOHN P. AGNEW, OF BROOKLYN, NEW YORK; SAID THURLOW ASSIGNOR TO SAID AGNEW.

GOLF-CLUB CARRIER.

Application filed August 23, 1927. Serial No. 214,960.

This invention relates to golf club carriers, an object of the invention being to provide a carrier which takes the place of the ordinary golf bag and which is very much lighter in weight than the ordinary bag.

A further object is to provide a container of the character stated which is ornamental and attractive in appearance and which will prevent the accumulation of dirt and dust 10 in the interior thereof because of the fact that it is open to circulation of air and will permit any dirt which falls from the clubs to drop out of the carrier.

A further object is to provide a carrier of 15 this character in which the clubs may be independently supported and which also provides a compartment for golf balls.

With these and other objects in view, the invention consists in certain novel features 20 of construction and combinations and arrangements of parts, which will be more fully hereinafter described and pointed out in the claims.

In the accompanying drawings—
25 Figure 1 is a perspective view of our improved golf club carrier;

Figure 2 is a view in longitudinal section, the view being taken on the line 2—2 of Figure 3;

30 Figure 3 is a view in top plan on an enlarged scale.

Our improved carrier comprises a pair of spaced disks 1 and 2, a plurality of spaced rings 3 and 4, and a top ring 5, all of which 35 are connected by longitudinal rods 6 arranged in circular series and preferably projected through perforations in the several disks and rings and secured in said perforations in any approved manner.

40 We have shown ordinary tacks 7 driven through the material of the disks and rings and into the rods, and we may employ such tacks when such rods are of wood, but it is of course to be understood that the invention is not limited to the material employed 45 as the parts may be of metal, fiber or any other suitable material, it being of course understood that these parts are designed for lightness of weight but must be sufficiently 50 strong to withstand the stresses to which the parts are put to use.

In addition to the circular series of rods 6 we provide a circular series of shorter rods 8 which extend through the disks 1 and 55 2 to form a ball compartment.

The upper ring 5 and the ring 4 are each provided with a circular series of aligned openings 9 large enough to receive the handle portions of golf clubs and allow the said clubs to be positioned within the carrier, 60 and preferably having their lower ends resting upon a pad 10 located on the disk 2 and preferably secured thereto by adhesive or in any other suitable manner.

The space between the disks 1 and 2 provides a compartment for the accommodation of golf balls, one of which is illustrated by the reference numeral 11. To permit access to and exit from this compartment, one of the rods 6 is cut off shorter than the others, 70 and a telescoping tubular rod 12 is located thereon and is movable through an opening 13 in the lower disk 1 and is held against such movement by a padlock 14 so that the golf balls may be securely locked in their 75 compartment.

On two of the rods 6 a pair of yokes 15 is secured and supports a handle 16, and a strap 17 is connected to one end of the handle 16 and at its other end is adjustable 80 in a loop 18 fixed to the ring 4. This handle allows the carrier to be conveniently carried in the hand, and the strap 17 is for use over the shoulder of the player or caddy, as is customary in the art.

85 A spike 19 is secured centrally in the bottom disk 1 and is adapted to project into the ground, as occasion may require, and this spike may be supported in a ring 3 when transporting the bag. The spike holds the 90 golf club carrier in an upright position when pressed into the ground thereby protecting the golf clubs from injury as happens in the prevailing golf bags now in use at the time the bag is dropped on the 95 ground.

It will thus be noted that with a carrier of this sort the golf clubs can be independently mounted in the several openings 9 in the two rings 4 and 5 with the major portion of said clubs located within the carrier, 100 and additional clubs or a sweater or other articles may be positioned through the central opening of the ring 5, so that the carrier affords a most useful, convenient ornamental 105 and attractive device which replaces the old heavier and more or less unattractive bags which have commonly been employed for the purpose.

Various slight changes and alterations 110

might be made in the general form of the parts described without departing from our invention and hence we do not limit ourselves to the precise details set forth but consider ourselves at liberty to make such changes and alterations as fairly fall within the spirit and scope of the appended claims.

We claim:

- 10 1. A device of the character described, including a pair of spaced disks at the base thereof, a ring at the top thereof, rings intermediate the top and disks, and a circular series of rods connecting said disks and rings, said top ring and an intermediately positioned ring having circular series of openings adapted to receive golf clubs therein.
- 15 2. A device of the character described, including a pair of spaced disks at the base thereof, a ring at the top thereof, rings intermediate the top and disks, a circular series of rods connecting said disks and rings, said top ring having a circular series

of openings adapted to receive golf clubs 25 therein, said spaced disks and said rods forming a ball compartment, and a movable member constituting a closure for said compartment, said last-mentioned member adapted to be locked in closed position. 20

3. A device of the character described, comprising a disk and a plurality of superimposed spaced rings spaced apart, longitudinal rods projecting through the disk and the rings and secured therein, said rods 35 forming an open compartment for golf clubs, the uppermost ring having openings therein to receive the clubs, a pair of yokes connecting at least two of the rods, a handle connecting the yokes, a loop on one of the 40 rings, a strap adjustably connecting the handle and said loop, and a spike in the lower end of the carrier.

Signed at Brooklyn, in the county of Kings and State of New York, this 22nd 45 day of August A. D. 1927.
